FRANK W. MERRICK, OF DORCHESTER, MASSACHUSETTS, ASSIGNOR TO WONDER WEAVE, INC., OF BOSTON, MASSACHUSETTS, A CORPORATION OF MASSACHUSETTS

SHEDDING MECHANISM FOR LOOMS

Application filed February 24, 1930. Serial No. 430,717.

In the patent to William S. Wells, No. 1,759,530 a warp-shedding mechanism is disclosed which, essentially stated, combines with a pair of actuators reciprocating in opposite directions together toward and together from an intermediate plane and each in a straight line, levers forming parts of the systems to shift the warps to form the sheds and each having a coupling means movable to intercouple the same with either actuator. In that case the actuator moves rectilineally, making a separate guide therefor necessary, and in order to control the coupling means by a pattern cylinder or the like having a definite position with reference to the rest of the mechanism it was necessary to take account of the fact that the actuator moved in a straight line whereas the coupling means followed the arcuate path of the lever, and this made necessary certain complications of structure and led to unreliability in action of the mechanism, especially when operated at high speed. The object of this invention is to overcome these faults, and this I accomplish by constructing the actuators as levers and providing a common fulcrum for them and the lever of each warp-shifting system.

In the drawings, Fig. 1 is a longitudinal sectional view through a mechanism embodying the invention, the actuators being together or in position for transfer;

Fig. 2 is a similar view, the actuators being apart to form the shed;

Fig. 3 is a section on line 3—3, Fig. 2;

Fig. 4 is a section on line 4—4, Fig. 1; and

Fig. 5 is a view somewhat similar to Fig. 1 but showing the means for moving the actuators and pattern cylinder, so much of such means as actuates the pattern cylinder appearing in modified form.

Each of the mentioned "systems" here includes a harness shaft 1 sliding vertically in guides 2 and having of course heddles or other provision (not shown) for receiving and imparting shed-forming movements to warps; a lever 3 fulcrumed on a shaft 4; and means, as links 5, to connect the shaft 1 with

the lever. Each lever here comprises two side bars 3a (Fig. 4) having spacers 3b between them so that the whole forms a unitary part, and the corresponding link extends between and is pivoted to these bars; but these details are immaterial.

The mentioned actuator levers, 6, are here shown as each comprising spaced legs 6a joined by a cross-bar 6b, or here U-shaped, the free ends of their legs being fulcrumed on the shaft 4, the pair of one member between those of the other and the group of levers 3 being flanked at each side by the corresponding legs of the actuators. The actuators receive motion up and down, so that they move together toward and together from each other, through links 7 from a double crank 8 on a shaft 9 whose crank 9a is connected with the rotating element 10 by a pitman 11.

Each mentioned "coupling means" here includes the coupling proper or coupler 12 having notches 12a to receive the cross-bars 6b of the actuator levers and pivoted between these notches to a lever 3 of one of said systems, a lever 13 fulcrumed at 14, a link 15 pivotally connecting this lever and the coupling, and a spring 16 connecting the lever with some fixed point 17.

18 is a cylinder having a peg or pegs or equivalent 18a to cause shifting of each lever 13 against the tension of spring 16 when such cylinder, serving as the pattern means, is rotated. This rotation may be effected step by step (Fig. 5) from a crank 19 on shaft 9 acting through pitman 20 to oscillate a crank 21 on the shaft 18b on which the cylinder rotates, said crank 21 having a spring pressed pick pawl 22 engaged with a ratchet 18c on the cylinder, which is kept from re-rotation by a holding pawl 23 engaging said ratchet. Or the shaft 10a of element 10 may carry the actuator 24 of a Geneva stop motion (Fig. 1) whose notched disk 25 is affixed to the cylinder. Any other means for rotating the cylinder intermittently and holding it fixed between movements may be utilized.

I here note that in Fig. 5, since either actuator lever 6 and the pawl 22 are both back-and-forth moving parts of the same back-and-

forth moving train, the transfer or shifting of a coupling cannot be advanced or retarded, in other words "timed", with respect to the time in a cycle of said train when it is in position for the transfer to occur, and this factor limits the speed at which the shedding mechanism may be driven. But in Fig. 1, where the part 10 (continually rotating in either case in one direction) and is therefore independent of said train, it is possible to obtain any necessary timing of the advances of the pattern means 18 with respect to the positioning of the actuator levers 6 for transfer by some such adjustment as of the actuator 16 24 of the Geneva stop motion around shaft 10 or it may be of the pattern means 18 around shaft 18b.

With the actuator levers reciprocating the coupler 12 of any one system will always be engaged with one or the other actuator lever. The transfer from one to the other actuator lever occurs when the actuator levers are in the proximating portions of their ranges of movement, or here in actual contact with the levers 3 as when a peg 18a causes displacement to the right or permits it to the left. Thus, according to the pattern determined by the arrangement of pegs on the rotated cylinder 18, any one shaft 1 may in a full cycle of the actuator levers move from the one to the other open-shed position or from one open-shed position to the mid-position and back, in the former case being transferred from one actuator to the other and in the latter remaining coupled with the same actuator, all as in the case of the Wells shedding mechanism referred to.

But, since the actuator levers are here fulcrumed on the same axis, 4, as the levers of the warp shifting systems the paths of movement of the couplers are parallel with the paths of the actuators, wherefore said axis itself serves to confine the actuators to definite paths of movement and no expedient for producing a differential movement of each coupling means with respect to its lever so as to insure the coupling remaining engaged with the actuator lever is necessary and the apparatus therefore operates with greater efficiency and may be driven at higher speed without accidental uncoupling.

My invention is not necessarily limited to the presence of two actuator levers movable together toward and together from an intermediate plane, and I claim accordingly.

Having thus fully described my invention what I claim is:

1. In a warp-shedding mechanism, the combination, with a warp-shifting system including a lever, of a back-and-forth-moving actuator lever, a common fulcrum for the levers, and coupling means movable at will to intercouple or uncouple said levers.

2. In a warp-shedding mechanism, the combination, with a warp-shifting system includ-

ing a lever, of a pair of actuator levers moving toward and from an intermediate plane, a common fulcrum for the several levers, and coupling means movable at will to intercouple the first lever and either actuator lever and uncouple the first lever and the other actuator lever.

3. In a warp-shedding mechanism, the combination, with a warp-shifting system including a lever, of a pair of actuator levers having the first lever between them, a common fulcrum for the several levers, said actuator levers being movable together toward and together from and adapted remote from the fulcrum to contact with the first lever, and means movable to intercouple the first lever and either actuator lever and uncouple the first lever and the other actuator lever during such contact.

4. In a warp-shedding mechanism, the combination of a fulcrum, warp-shifting systems each including a lever, said levers being arranged on said fulcrum, a back-and-forth moving actuator lever having two spaced lever legs arranged on said fulcrum and a cross-bar connecting said legs, the first levers being arranged between the legs of the actuator lever, and coupling means movable on the respective first levers into and out of engagement with said cross-bar.

5. In a warp-shedding mechanism, the combination of a fulcrum, warp-shifting systems each including a lever, said levers being arranged on said fulcrum, back-and-forth moving actuator levers each having two spaced lever legs arranged on said fulcrum and a cross-bar connecting said legs, the first levers being arranged between the actuator levers and also between the legs thereof, and coupling means movable on the respective first levers into and out of engagement with each cross-bar.

In testimony whereof I affix my signature.
FRANK W. MERRICK.
